PULL FOR A DRAWER

Anthony Joseph Carsello, Hollywood, Calif., assignor to
Ajax Hardware Manufacturing Corp., City of Industry,
Calif., a corporation of California

Filed Sept. 25, 1964, Ser. No. 81,879

Term of patent 14 years

(Cl. D10—8)

FIG. 1.

FIG. 2.

FIG. 3.

FIG. 4.

FIG. 5.

FIG. 1 is an isometric view of a pull for a drawer, showing my new design;

FIG. 2 is a front elevational view;

FIG. 3 is a rear elevational view;

FIG. 4 is a top plan view; and

FIG. 5 is an end elevational view.

I claim:

The ornamental design for a pull for a drawer, as shown.
